UNITED STATES PATENT OFFICE.

HENRY BREHMER, OF CASTLETON, ASSIGNOR TO DAVID WOLFE BRUCE,
OF NEW YORK, N. Y.

DESIGN FOR TYPE.

SPECIFICATION forming part of Design No. 17,479, dated July 26, 1887.

Application filed December 17, 1886. Serial No. 221,994. Term of patent 14 years.

To all whom it may concern:

Be it known that I, HENRY BREHMER, (assignor to DAVID WOLFE BRUCE,) of Castleton, Richmond county, New York, have invented 5 a new Design for a Font of Printing-Type, of which the following is a specification.

The nature of my design is clearly shown in the accompanying typographic impression, to which reference is made; and it consists of 10 an unshaded letter having at its upper right hand, as in the E, F, H, K, N, U, V, and W, the short curved line with open-dot termination, and in the A, B, D, E, F, H, I, J, K, L, M, N, P, R, U, V, W, X, and Y, at the upper left hand, the short curved line with dot termination. The short curved line with dot termination is also found at the base of the B, D, E, F, H, I, K, L, M, N, P, R, S, T, X, and Y upon the left hand. The faces of the D, O, Q, 15 and U are ornamented by the tendril-like ornaments. The A, F, H, M, X, and Y are extended below the line upon the right. The cross-line of the A and H terminates upon the left in the flourish. The C is ornamented upon the right by the inclined line having the dot 20 termination at its base upon the right hand, the rounding portions of the B, C, G, and R terminating in the dot termination. The G and S are ornamented upon the right by the inclined line having the dot termination at its base upon the right hand, both the upper 25 terminations of the T consisting of the curved lines with open-dot termination, the right-hand and left-hand portions of the W extending beyond the central portion looped, as shown, both terminations of the Z formed of the curved lines with open-dot termination, and the character of the design preserved in 30 the symbol &, the punctuation-marks, the numerals, and dollar and pound-sterling marks. 35

The character of the design is preserved in the symbol &, the punctuation-marks, the 40 numerals, and the dollar and pound-sterling marks.

Having described my invention, I claim as new—

The design for a font of printing-type, which consists of an unshaded letter having at its 45 upper right hand, as in the E, F, H, K, N, U, V, and W, the short curved line with open-dot termination, and in the A, B, D, E, F, H, I, J, K, L, M, N, P, R, U, V, W, X, and Y, at the upper left hand, the short curved line 50 with dot termination, the short curved line with dot termination also found at the base of the B, D, E, F, H, I, K, L, M, N, P, R, S, T, X, and Y upon the left hand, the faces of the D, O, Q, and U ornamented by the tendril-like 55 ornaments, the A, F, H, M, X, and Y extended below the line upon the right, the cross-line of the A and H terminating upon the left in a flourish, the C ornamented upon the right by the inclined line having the dot 60 termination at its base upon the right hand, the rounding portions of the B, C, G, and R terminating in the dot termination, the G and S ornamented upon the right by the inclined line having the dot termination at its 65 base upon the right hand, both the upper terminations of the T consisting of the curved lines with open-dot termination, the right-hand and left-hand portions of the W extending beyond the central portion looped, as 70 shown, both terminations of the Z formed of the curved lines with open-dot termination, and the character of the design preserved in the symbol &, the punctuation-marks, the numerals, and dollar and pound-sterling marks, 75 all as shown and described.

HENRY BREHMER.

In presence of—

WILLIAM V. H. HICKS,
A. SIDNEY DOANE.
